UNITED STATES PATENT OFFICE.

GEORGE D. LOUD, OF BOSTON, MASSACHUSETTS.

PUMPING UNIT.

1,169,752.

Specification of Letters Patent. Patented Jan. 25, 1916.

Application filed December 5, 1914. Serial No. 875,698.

To all whom it may concern:

Be it known that I, GEORGE D. LOUD, a citizen of the United States, residing at Boston, in the county of Suffolk and State 5 of Massachusetts, have invented certain new and useful Improvements in Pumping Units; and I do hereby declare the following to be a full, clear, and exact description of the invention, such as will enable others 10 skilled in the art to which it appertains to make and use the same.

The present invention relates to pumping units and more particularly to portable units comprising an internal combustion motor 15 and a reciprocating pump arranged in compact relation to one another.

One object of the present invention is to provide a portable pumping unit comprising an internal combustion motor and a 20 hydraulic pump supported upon a single base and having an improved construction and arrangement of the various operating parts to provide a simplified and compact form of pumping unit.

25 The type of pumping unit most generally employed where it is necessary that the unit be of a portable nature comprises a diaphragm pump which is manually actuated by an oscillating lever. This type of pump 30 may be used to advantage as it is conveniently transported from place to place and will pump liquid which contains grit, sediment, and even pieces of stone, but upon the other hand, the capacity is relatively 35 small and requires the constant attention of two men to operate the pump. It is very desirable, therefore, that this type of pump be operated mechanically and that the motor is so arranged that it may be applied 40 to manually actuated pumps without substantial change in the pumps themselves.

A further object of the invention, therefore, consists in a self contained motor 45 which may be detachably secured to a pump of this character in place of the manually operated mechanism without the necessity of altering the pump itself.

With the above objects in view the several 50 features of the invention consist in certain novel features of construction, combinations and arrangements of parts hereinafter described and claimed, the advantages of which will be obvious to those skilled in 55 the art from the following description.

In the accompanying drawings illustrat-

ing the preferred form of the invention; Figure 1 represents a longitudinal section in elevation of the pumping unit; Fig. 2 is an elevation partly in section taken at 60 right angles to the view shown in Fig. 1; Fig. 3 is an elevation partly in section of the motor and connected mechanism adapted for attachment to the pump casing; and Fig. 4 is a sectional elevation of the diaphragm pump showing in dotted outline the manually operated mechanism which is removed from the pump to permit the application of the motor.

The pumping unit shown in the illustrated embodiment of the invention comprises a pump having a casing, a diaphragm supported in the casing, suction and delivery valves, and a motor having a crank case adapted for attachment directly to the 70 pump casing, a pair of crank shafts connected by reducing gearing, and a crosshead having provision for connection to the diaphragm of the pump. The provision of the motor and connected mechanism so constructed that they may be readily attached 75 to a pump enables the pump to be operated either by hand or mechanically, and so facilitates the interchanging of the two mechanisms that the pumping unit may be 80 readily changed from hand operated to motor operated, or vice versa.

A well-known type of diaphragm pump is shown in the drawings comprising a pump casing open at the upper end and 90 formed of two sections indicated at 1 and 2, respectively and having the edges of a flexible diaphragm 3 clamped between them by clamping bolts 4. As shown clearly in Fig. 1 of the drawings, the pumped water is 95 taken in through a suction valve 6 and is delivered by a valve indicated at 7 which is located in the center of the movable diaphragm. With this construction the water is delivered above the diaphragm through 100 the open upper end of the pump. The flexible diaphragm is of an annular form and is clamped at its inner edges by the clamping heads 8 and 9 which are secured together in the usual manner by elongated 105 clamping bolts 10 supported in standards 11 and adapted for attachment at their upper ends to a reciprocating crosshead. The ends of the crosshead pass over the bolts and are secured to the standards through clamping 110 nuts 12. In the ordinary type of hand operated pump the crosshead is of the shape

shown in dot and dash outline in Fig. 4 and is engaged by the toe of an oscillatory lever fulcrumed upon any one of a series of inturned brackets or supports 15 projecting 5 from the upper edge of the pump casing. These supports are of the usual form and are slotted to receive T-shaped bolts, as shown clearly in the drawings. This construction and arrangement detachably connects the operating mechanism to the pump 10 and at the same time permits the position of the handle to be changed in accordance with varying conditions.

In the present invention the pump proper 15 may be mechanically operated without change and in order to adapt the pump for the reception of the motor it is only necessary to remove the hand operated lever by loosening the T bolt, and the crosshead by removing 20 the two clamping nuts 12. The motor and connected mechanism comprises an internal combustion motor and crosshead adapted for connection directly to the clamping bolts 10, and a crank case for the 25 motor having provision for attachment directly to the brackets 15, the connecting means being arranged to position the motor properly with relation to the pump and secure it firmly in this position to withstand 30 any vibration which may occur.

The motor comprises an air cooled power cylinder 16 having the usual cooling fins 17, connecting rod 18, and a crank shaft 19 journaled in a crank case 20. As it is advisable 35 to drive the pump at a slower speed than the normal speed of operation of the motor, speed reducing mechanism is embodied in the motor, and a pump actuating crank shaft is connected to the motor crank shaft 40 through the reducing gearing. To this end a second crank shaft 22 is journaled in the crank case at right angles to and above the crank shaft 19 and is driven thereby through the intermeshing worm gears 23 and 24. 45 The motor crank shaft 19 is provided upon one end with a fly wheel 25 and is supported at the opposite end by a thrust bearing indicated at 26 to counteract the thrust imparted by the action of the worm gearing. 50 The motor receives its lubrication in the usual manner from a lubricating medium contained in the pit 28 of the crank case and splashed therefrom by the rotation of the crank shaft. As the reducing gearing 55 and crank shaft 22 are also supported in the same casing, the same lubricating medium also conveniently serves for the lubrication of these parts. As shown clearly in Fig. 1 of the drawings, the shaft 22 projects from the casing 20 and is provided upon its opposite ends with cranks 30 which are provided with connecting rods 31. The rods 31 are connected to the diaphragm by a crosshead 32 and a cross pin 33 supported 60 transversely in the crosshead connected at

its opposite ends to the lower ends of the rods. The crosshead is permanently connected to the crank shaft 22 and forms an integral part of the motor, and by slipping the ends of the crosshead over the clamping bolts and adjusting the clamping nuts 12 the motor is readily connected to the pump without changing the latter. In order to guide the crosshead in its movements and prevent an undue vibration of the apparatus oppositely disposed vertical guides 35 and 36 are secured to the crank case and engage with and form bearings for the enlarged ends 37 of the connecting rods, as shown clearly in Fig. 2. The crank case is 80 provided with means for enabling the motor to be readily attached to the pump and for causing the motor to be properly positioned with relation to the pump so that the operating connections of the pump and motor 85 may be properly connected with one another. To this end a depending leg 40 is formed upon the crank casing adjacent to the fly wheel, and a pair of depending legs 42 are formed upon opposite sides of the crank 90 case. Each of these legs is provided with an out-turned foot 43 which is slotted to receive T-shaped clamping bolts 45 engaging with the under side of the brackets 15 to join the motor and pump rigidly together. 95 The supporting and connecting legs are arranged to align with the three supporting brackets when the motor and pump are in operative relation to one another, thus causing the crosshead of the motor to be readily connected with the diaphragm of the pump without the necessity for adjustment in each individual case.

It will be obvious in view of the foregoing description that with this construction the motor or the hand operated mechanism may be connected directly to the diaphragm of the pump with equal facility by simply removing the crosshead and T-shaped clamping bolts and replacing them by a new crosshead and clamping bolts. Furthermore, it will be observed that when the pump is operated by the motor no enlargement or extension of the base is necessary and the unit is even more compact than when operated by hand as the motor is supported entirely by the pump casing and requires substantially no greater floor room than the pump casing itself.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:

1. A pumping unit, having in combina- 130

tion, a pump casing, a diaphragm supported in the casing, a motor having a crank case detachably secured to and supported by the pump case, a motor crank shaft and a pump 5 crank shaft supported in the crank case directly above the diaphragm, reducing gears connecting the two shafts, a crosshead located outside of the crank case and connected to the diaphragm, and connections between the crosshead and pump shaft.

2. A pumping unit, having in combination, a pump casing, a movable pump member supported in the casing, a motor crank case, a motor crank shaft and a pump crank 15 shaft supported at right angles to one another in the crank case, worm gearing connecting the two shafts, a crosshead secured to the movable member of the pump, and rods connecting the opposite ends of the 20 pump shaft outside of the crank case with the crosshead.

3. A pumping unit comprising a pump casing, a motor crank case detachably secured to and supported by the pump casing, 25 a motor crank shaft and a pump shaft supported in the crank case, reducing gears connecting the two shafts, a connecting rod secured to the pump shaft, and a crosshead supported by the rod outside of the crank 30 case and adapted for attachment to a movable pump member.

4. A pumping unit comprising a pump casing having a series of inturned lugs, a motor crank case, a plurality of legs formed 35 upon the crank case and arranged to cooperate with the corresponding lugs formed upon the pump casing, a motor crank shaft and a pump crank shaft supported in the crank case, connecting rods secured to the 40 pump shaft outside of the crank case, a

crosshead supported by the connecting rods, and guide members supported by the crank case and coöperating with the crosshead.

5. A pumping unit, having in combination, a pump casing provided with a series 45 of inturned supports at its upper edge, a movable diaphragm supported in the casing, a motor crank case having feet coöperating with the supports to support the crank case upon the pump casing above the pump, a 50 motor crank shaft, a crosshead secured to the diaphragm, and connections between the motor crank shaft and the crosshead.

6. A pumping unit, having in combination, a pump casing open at its upper end, a 55 movable pump member supported in the casing, a suction valve, a delivery valve arranged to discharge water above the pump member through the open upper end of the pump casing, a motor having a crank case 60 detachably secured to and supported above the pump casing, a motor crank shaft supported in the crank case, and detachable connections between the movable pump member and the crank shaft. 65

7. A pumping unit, having in combination, a pump casing open at its upper end, a diaphragm supported in the casing, a motor having a crank case detachably secured to and supported above the pump casing, a 70 motor crank shaft supported in the crank case, a crosshead detachably secured to the diaphragm outside of the crank case, and connections between the diaphragm and the crank shaft.
